METALLIC VESSEL FOR HIGH TEMPERATURE SERVICE

Charles L. Norton, Jr., New York, N. Y., assignor
to The Babcock & Wilcox Company, Jersey
City, N. J., a corporation of New Jersey

Application October 17, 1942, Serial No. 462,359

18 Claims.

(Cl. 266—24)

The present invention relates in general to the construction of apparatus for heating material to a temperature above 1000° F. and including a container or pressure vessel adapted to contain the material to be heated and formed of a metal subject to corrosion when exposed to corrosive conditions at such temperatures. More particularly, my invention relates to the construction of apparatus for the production of metallic magnesium by the reduction of a charge of a magnesium-containing material in a furnace retort under a substantial vacuum, as disclosed in my prior joint application with James Fletcher, Serial No. 450,472, filed July 10, 1942.

Ordinary iron or steel having a melting point of 2700° F.—2900° F. oxidizes comparatively rapidly at temperatures above 930° F. and for this reason ferrous structures are ordinarily limited to use under service temperatures below 900° F. For effective resistance to scaling at high temperatures, it is usually considered necessary to use a corrosive resistant alloy steel for at least the exposed surface of the structure. Even such structures are not wholly satisfactory for prolonged use at temperatures above 2000° F. and moreover are expensive to manufacture and require a substantial amount of alloy metal. The problem is further complicated by the loss of strength and increase of permeability of plain and alloy steels at high temperatures.

The general object of my invention is the provision of apparatus for heating a charge of material to a temperature substantially above 1000° F. in a container or pressure vessel formed of a metal subject to rapid corrosion when exposed to corrosive conditions at such temperatures. A further and more specific object is the provision of a pressure vessel of non-alloy ferrous metal with an external protective covering of a non-corrosive fluid or semi-fluid ceramic material permitting the use of the vessel for long periods under corrosive conditions at temperatures substantially above the temperatures at which the vessel could safely be used in an exposed condition. A still further object is the provision of a furnace retort having a shell made of a non-alloy ferrous metal and protective means making it capable of use with a substantial vacuum therein under furnace temperature conditions maintaining a metal temperature above 2000° F. for long periods.

The various features of novelty which characterize my invention are pointed out with particularity in the claims annexed to and forming a part of this specification. For a better understanding of the invention, its operating advan-

tages and specific objects attained by its use, reference should be had to the accompanying drawings and descriptive matter in which I have illustrated and described preferred embodiments of my invention.

Of the drawings:

Fig. 1 is a sectional elevation of a magnesium reduction furnace incorporating a retort constructed in accordance with my invention;

Fig. 2 is a partial longitudinal section of the furnace taken on the line 2—2 of Fig. 1;

Fig. 3 is a view similar to Fig. 1 illustrating a modified furnace and retort construction; and

Fig. 4 is a view similar to Fig. 2 taken on the line 4—4 of Fig. 3.

While the apparatus of my invention is adapted for a variety of uses where a vessel of corrodible or oxidizable metal is subjected to corrosive service conditions at temperatures above 900° F., it is particularly designed for and especially useful in the construction of retorts for the production of metallic magnesium by the reduction of a magnesium containing material at a temperature of 2100°—2300° F. and under a substantial vacuum.

In the normal operation of this process dolomitic limestone is burned and pulverized to a finely divided condition; it is then mixed with a predetermined amount of a pulverized reducing agent, preferably ferro-silicon. The pulverized

dolomite and ferro-silicon in the form of small briquets are charged into an externally heated metallic retort which is kept under a high vacuum by means of a suitable vacuum pump. The charge in the retort is heated to a temperature of approximately 2100°—2300° F., i. e. above the vaporization temperature of magnesium which is usually considered as 1958°—2048° F. A chemical reaction occurs between the burned dolomite and ferro-silicon resulting in the reduction of the magnesium oxide and the formation of magnesium, calcium silicate, and iron. The operating pressure within the retort is maintained as low as possible, preferably at an absolute pressure of 0.1 mm. Hg.

Such a high vacuum has been found to minimize wastage of the silicon by oxidation, formation of magnesium nitride, and discoloration and sponginess of the condensed magnesium. The vaporized magnesium passes into the condenser section of the retort where it is condensed and recovered in a solid dense crystalline mass 99.98% pure. The condensed metal is removed from the retort, subsequently melted down under flux, and poured into ingots.

In Figs. 1 and 2 I have illustrated a furnace designed for the described process of reduction

of magnesium ore. The furnace 10 is of substantially rectangular cross-section with an arched roof 11 containing spaced gas outlets 12. The furnace is heated by rows of fluid fuel burners 13, such as gas, oil or pulverized fuel burners, oppositely arranged in the lower part of the side walls 14 and positioned between transverse refractory partitions 15 extending the full width of the furnace. Movable baffles 16 are arranged between the partitions to control the heating gas flow. Short firebrick piers 17 are spaced along the top of each partition 15, and serve as supports for a corresponding horizontally elongated retort 20 extending substantially the full width of the furnace chamber. Due to the high retort metal temperatures in operation, the corrosive furnace atmosphere, and the high vacuum maintained within the retort, it has been considered essential to make such retorts of cast stainless steel, such as an alloy of 25% chrome, 20% nickel, with the balance substantially all iron. Such alloy metal however is expensive, and under war conditions relatively scarce, and such retorts normally have a relatively short life in service. In accordance with my invention, such stainless steel retorts can be economically replaced by retorts made of non-alloy ferrous metal having a protective covering preventing oxidation or corrosion of the retort metal under the service conditions described.

The retort 20 illustrated has a body or shell 21 formed by an extra heavy pipe of mild steel. One end of the pipe is spun inwardly to form a rounded end portion 22 having a circular center opening which is closed by a metal plug 23 conforming in contour to the retort opening and welded therein to form a gas-tight closure. The opposite or outer end of the retort shell is provided with an external peripheral flange 24 welded thereto. An end plate 25 is connected to the flange 24 in any suitable manner to form a gas-tight detachable closure for the retort, adapted to be removed for the charging and discharging of the retort. The outer end portion of the retort is constructed to form a magnesium vapor condensing section by means of a water cooled circumferential jacket 26 having water inlet and outlet connections 27 and 28 respectively. A cylindrical metallic sleeve 30 is arranged to closely fit within the condenser section of the shell with its outer end secured to the end plate 25 in any suitable manner. An outer section of the sleeve 30 is slotted as indicated at 31 to connect the interior of the shell to a short pipe 32 to which a vacuum pump (not shown) is detachably connected. In operation the magnesium vapor condenses on the sleeve 30, which is removed with the end plate 25 at the end of the heating period and the condensed magnesium removed. A fresh charge of briquets is then placed in the retort and the sleeve and end plate restored to their original position.

With a retort metal temperature of 2100°-2300° F. and a corrosive atmosphere, a non-alloy ferrous metal shell has been found to have a service life of only a relatively few hours before the oxidation and scaling of the metal progresses to such an extent that the desired vacuum could no longer be maintained or the thinning of the shell wall and pressure differential thereon caused the shell to collapse. In accordance with my invention the portion of the shell beyond the condenser section which extends into the furnace chamber is covered with or immersed in a protective material which effectively prevents cor-

rosion and scaling of the ferrous metal shell 21 under the contemplated service conditions.

In the embodiment illustrated in Figs. 1 and 2, the protective covering comprises an outer substantially fluid-tight container 35 of similar shape but larger dimensions than the shell 21 and formed of high temperature refractory material which is not affected by the surrounding corrosive furnace atmospheric conditions. The container 35 can be made in a single piece, but more advantageously is made of overlapping sections of dense ceramic refractory material fired during its manufacture to a temperature above the contemplated furnace temperature. A wide variety of compositions are suitable for this purpose, such as silicon carbide or the ceramic mixes used for dense sewer pipe or chemical stoneware. The sections are sealed at the overlap by a high temperature refractory cement.

The annular and end spaces between the shell 21 and container 35 are filled with a sealing material 40 having a softening point several hundred degrees F. below the contemplated service temperatures and fluid enough at service temperatures to wet the metal surface of the shell. The sealing material must not alloy with the metal of the shell or have a high vapor pressure at the contemplated service temperatures. For service temperatures in the range of 2100°-2300° F. I have found various mixtures of ceramic materials, such as sodium silicate, raw clay, calcined clay, and silica sand highly effective protecting mediums. By way of example and not of limitation, the following mixtures were found suitable:

	A	B	C
	Per cent	Per cent	Per cent
Cooley ball clay.....	26	26	26
Silica sand—35 mesh.....	45	30	15
Calcined clay—40 mesh.....	15	30	45
Sodium silicate (dry).....	14	14	14

In preparing each of such mixtures, water equal to about 19% of the weight of the dry ingredients was added and the space between the shell and container filled with the mixture. Small refractory blocks 42 were used at intervals between the shell and container to center the shell within the container. The retort was then heated in a drying chamber until most of the moisture and gaseous constituents of the sealing layer had been driven off. The retort is then ready for service in the reduction furnace.

In operation, the retort is rapidly heated up to the service temperature with the ceramic sealing layer 40 gradually softening to a viscous bubbly mass filling the space between the shell and container. Under service conditions this viscous layer of ceramic material acts as a gas-tight impervious seal, preventing any furnace gases penetrating the refractory container wall from coming into contact with the shell metal, even with the described substantial pressure differential between the inside and outside of the retort. The shell metal thus remains uncorroded and capable of withstanding for long periods the high temperatures to which it must be heated for reduction of its magnesium ore charge.

In Figs. 3 and 4, I have illustrated another embodiment of my invention in which the container for the retort shell protecting layer of ceramic material is formed by the furnace walls and floor. In this construction the lower part of the furnace is lined with dense refractories of substantially the same composition as that suitable for glass

tank blocks to form a series of side-by-side elongated chambers 50 extending the full width of the furnace. Each chamber has refractory side walls 51 extending upwardly from the furnace floor 52 and formed of glass tank blocks. The bottom 53 of each chamber is formed of similar refractories shaped to slope downwardly from the walls 51 and side walls 14 of the furnace to a central discharge opening 54 above a larger opening 55 in the furnace floor. In operation, the hole 54 is closed by a suitable clay plug 56, which can be removed to drain the corresponding chamber 50. Refractory tile blocks 58 extend between the side walls 51 at spaced points and are cut away on their upper sides to receive and support the non-alloy ferrous retort shell 21.

The chambers 50 form containers for a bath or batch of ceramic protective material 60 of the same general character as, but preferably more fluid at the contemplated service temperatures than the ceramic material 40 used in the construction shown in Figs. 1 and 2. Ordinary soda-lime glass, such as 73% SiO₂, 5% CaO, and 22% Na₂O, is quite satisfactory for service temperatures in the 2100°-2300° F. range, but any material which will not alloy and combine with the retort shell metal and has a low vapor pressure and is sufficiently fluid at the service temperatures can be used. Baths of fused borax, barium chloride, sodium fluoride, or sodium disilicate are also considered suitable for this purpose. In starting-up the chambers 50 are filled with sufficient protective material, such as broken or powdered glass, to provide an amount when fused sufficient to immerse or submerge the retort as shown in Figs. 3 and 4. In this construction the fuel burners 13 are alternately arranged at opposite sides of the furnace above the corresponding chambers 50 to provide a substantially uniform heating effect throughout the width of the chambers.

In operation the retorts are charged as previously described and the reducing operation takes place at a temperature in the 2100°-2300° F. range. The bath material provides an efficient heat conducting medium to the retort shell and included charge. A high fluidity of the bath material and the sectioning of the furnace tends to promote a circulation of the ceramic bath material around the immersed retorts without permitting contact between the corrosive constituents of the furnace atmosphere and the retort shell. If desired, the walls separating the chambers 50 can be omitted to provide a common bath of protecting material for the retorts.

While in accordance with the provisions of the patent statutes I have illustrated and described herein the best forms of the invention now known to me, those skilled in the art will understand that changes may be made in the form of the apparatus disclosed without departing from the spirit of the invention covered by my claims, and that certain features of the invention may sometimes be used to advantage without a corresponding use of other features.

I claim:

1. Apparatus for heating a material to temperatures above 1000° F. which comprises a body member adapted to contain the material to be heated and formed of a metal subject to rapid corrosion when exposed to corrosive conditions at said temperatures, a heat resistant protective covering for said body member comprising a layer of ceramic material chemically inert relative to

said metal and in a sufficiently fluid condition when heated to said temperatures to wet the surface of said body member, and ceramic refractory means forming a container for holding said ceramic material in contact with said body member.

2. Apparatus for heating a material to temperatures above 1000° F. which comprises a body member adapted to contain the material to be heated and formed of a non-alloy ferrous metal subject to rapid corrosion when exposed to corrosive conditions at said temperatures, a heat resistant protective covering for said body member comprising a layer of ceramic material chemically inert relative to said metal and in a sufficiently fluid condition when heated to said temperatures to wet the surface of said body member, and ceramic refractory means forming a container for holding said ceramic material in contact with said body member.

3. Apparatus for heating a material to temperatures above 2000° F. which comprises a hollow body member adapted to contain the material to be heated and formed of a metal subject to rapid corrosion when exposed to corrosive conditions at said temperatures, means forming a heat resistant protective covering for said body member comprising a layer of ceramic material in contact with the outer surface of said body member, said ceramic material being viscous when heated to said temperatures and chemically inert relative to said metal, and ceramic refractory means forming a container for holding said ceramic material in contact with said body member.

4. A pressure vessel capable of use under a high vacuum therein and temperatures above 2000° F. which comprises a hollow body member adapted to contain a material to be heated and formed of a non-alloy ferrous metal subject to rapid corrosion when exposed to corrosive conditions at said temperatures, means forming a heat resistant protective covering for said body member comprising a layer of ceramic material in contact with the outer surface of said body member, said ceramic material being viscous when heated to said temperatures and chemically inert relative to said metal, and ceramic refractory means forming a container for holding said ceramic material in contact with said body member.

5. Apparatus for heating a material to temperatures above 1000° F. which comprises a shell adapted to contain the material to be heated and formed of a metal subject to rapid corrosion when exposed to corrosive conditions at said temperatures, a heat resistant protective covering for said shell including a layer of ceramic material contacting with the outer surface of said shell, said ceramic material being viscous when heated to said temperatures and chemically inert relative to said metal, and ceramic refractory means forming a container for holding said ceramic material in contact with said shell.

6. Apparatus for heating a material to temperatures above 2000° F. which comprises a shell adapted to contain the material to be heated and formed of a non-alloy ferrous metal subject to rapid corrosion when exposed to corrosive conditions at said temperatures, a heat resistant protective covering for said shell including a layer of ceramic material contacting with and in a sufficiently fluid condition when heated to said temperatures to wet the outer surface of said shell, and ceramic refractory means forming a container for holding said ceramic material in contact with said shell.

7. A furnace retort capable of use under corrosive conditions at metal temperatures above 2000° F. which comprises a shell of non-alloy ferrous metal subject to rapid corrosion when exposed to said service conditions, a heat resistant protective covering for said shell including a layer of chemically inert ceramic material contacting with and in a sufficiently fluid condition when heated to said temperatures to wet the outer surface of said shell, and ceramic refractory means forming a container for holding said ceramic material in contact with said shell.

8. A furnace retort capable of use under corrosive conditions at temperatures above 1000° F. which comprises a shell of metal subject to rapid corrosion when exposed to said service conditions, and a heat resistant protective covering for said shell including an inner layer of ceramic material neutral relative to said shell metal and contacting with the outer surface of said shell, and an outer member of refractory material forming a container holding said viscous inner layer in contact with said shell.

9. A furnace retort capable of use under corrosive conditions at temperatures above 2000° F. which comprises a shell of ferrous metal subject to rapid corrosion when exposed to said service conditions, and a heat resistant protective covering for said shell including an inner layer of ceramic material viscous when heated to said temperatures and neutral relative to said shell metal and contacting with the outer surface of said shell, and an outer layer of dense refractory material covering said viscous inner layer and forming a container holding the same in contact with said shell.

10. A retort for the reduction of magnesium ore under a high vacuum and capable of use under corrosive conditions at temperatures above 2000° F. which comprises a cylindrical pressure vessel of non-alloy ferrous metal subject to rapid corrosion when exposed to said service conditions, and a heat resistant protective covering for said pressure vessel including an inner layer of ceramic material viscous when heated to said temperatures and neutral relative to said metal and contacting with the outer surface of said vessel, and an outer cylinder of refractory material covering said viscous inner layer and forming a container holding the same in contact with said vessel.

11. A furnace for heating material to temperatures above 1000° F. comprising a furnace bottom constructed to receive a body of ceramic material chemically inert relative to ferrous metal, a fuel burner above the level of said body of ceramic material, and a retort for said material having a body of a ferrous metal subject to rapid corrosion when exposed to corrosive conditions at temperatures above 1000° F. and submerged in said body of refractory material.

12. A furnace for heating material to temperatures above 2000° F. comprising a furnace bottom constructed to receive a pool of ceramic material chemically inert relative to ferrous metal and in a viscous condition when heated to said temperatures, a fuel burner above the level of said pool of ceramic material, and a pressure vessel for said material having a body of a ferrous metal subject to rapid corrosion when exposed to corrosive conditions at temperatures above 2000° F. immersed in said pool of ceramic material.

13. A furnace for the reduction of magnesium ore at temperature above 2000° F. and under a

high vacuum comprising a furnace bottom constructed to receive a pool of ceramic material chemically inert relative to ferrous metal and in a viscous condition when heated to said temperatures, a fuel burner above the level of said pool of ceramic material, and a retort for said magnesium ore having a body of a non-alloy ferrous metal subject to rapid corrosion when exposed to corrosive conditions at temperatures above 2000° F. and immersed in said pool of ceramic material.

14. A furnace for the reduction of magnesium ore at temperatures above 2000° F. and under a high vacuum comprising a furnace bottom constructed to receive a pool of ceramic material chemically inert relative to ferrous metal and in a viscous condition when heated to said temperatures, a fuel burner above the level of said pool of ceramic material, a retort for said magnesium or having a body of a non-alloy ferrous metal subject to rapid corrosion when exposed to corrosive conditions at temperatures above 2000° F. and immersed in said pool of ceramic material, and means for charging said retort with magnesium ore and a reducing agent.

15. A furnace for heating material to temperatures above 1000° F. comprising a metallic tubular container for the material to be heated formed of metal subject to corrosion when exposed to corrosive conditions at said temperatures, ceramic refractory means forming a container for a bath of protective material in which said tubular container is immersed, said protective material being chemically inert relative to said metal and in a viscous condition when heated to said temperatures, and means for heating said bath of protective material.

16. A furnace for heating material to temperatures above 1000° F. comprising means forming a ceramic refractory container for a bath of molten ceramic material chemically inert relative to ferrous metal and in a viscous condition when heated to said temperatures, means for heating said bath of ceramic material, and a tubular container for the material to be heated formed of ferrous metal and immersed in said bath of ceramic material.

17. A furnace for heating material to temperatures above 1000° F. comprising refractory side walls and a bottom forming a container for a bath of molten protective material chemically inert relative to ferrous metal and in a viscous condition when heated to said temperatures, means for heating said bath of protective material, and a tubular container for the material to be heated formed of ferrous metal subject to corrosion when exposed to corrosive conditions at said temperatures and extending through one of said side walls below the upper level of and immersed in said bath of protective material.

18. A furnace for the reduction of a metallic ore at temperatures above 1000° F. comprising means forming a container for a bath of molten ceramic material chemically inert relative to ferrous metal and in a viscous condition when heated to said temperatures, means for heating said bath of ceramic material, and a retort for said metallic ore having a body of ferrous metal subject to corrosion when exposed to corrosive conditions at said temperatures and having an external condensing section and an inner heating section immersed in said bath of ceramic material.

CHARLES L. NORTON, JR.
